UNITED STATES PATENT OFFICE.

ZEMACH AUERBACH, OF NEW YORK, N. Y.

APPOINTMENT RACK OR CARD.

1,414,720.

Specification of Letters Patent. Patented May 2, 1922.

Application filed December 14, 1921. Serial No. 522,333.

To all whom it may concern:

Be it known that I, ZEMACH AUERBACH, a citizen of Russia, and resident of New York city, borough of Manhattan, in the county of New York and State of New York, have invented certain new and useful Improvements in Appointment Racks or Cards, of which the following is a specification.

10 The object of my invention is to provide a device comprising a slotted supporting member and cards movably carried thereby, upon which cards names of customers, patients and the like, may be written or 15 printed, and which cards may be removed and replaced as required, a further feature of my invention relating to means to indicate hours of time in connection with cards for indicating appointment hours.

20 My invention comprises novel details of improvement that will be more fully hereinafter set forth and then pointed out in the claims.

Reference is to be had to the accompanying drawings, forming part hereof, wherein

25 Figure 1 is a front view illustrating my improvement;

Fig. 2 is a plan view of Fig. 1;

Fig. 3 is an exaggerated section on line

30 3, 3, in Fig. 1;

Fig. 4 is an enlarged fragmentary view, illustrating component parts of the device;

Fig. 5 is a detail of one member of the rack;

35 Fig. 6 is a front view, illustrating the device with a single row of slots for cards, illustrating also a card adapted to hinge while attached to the rack for receiving memoranda on opposite faces;

40 Fig. 7 is a view similar to Fig. 6 but illustrating the manner of applying and detaching the card;

Fig. 8 is a section on line 8, 8, in Fig. 6, and

45 Fig. 9 is a section on line 9, 9, in Fig. 6. Similar numerals of reference indicate corresponding parts in the several views.

The main body of the support or rack comprises two sheets 1, 2, of paper or other suitable material to be placed face to face one against the other to receive and support movable cards 3. Each sheet 1, 2, is cut substantially similarly by means of spaced transverse slots 4 in the mid-portion of the sheet, the end portions 4^a of which slots are cut substantially at right angles to the

slots 4, providing the transversely disposed tongues 5. By preference the end edges 5^a of said tongues extend at an oblique angle to the transverse edges of the tongues, which is provided by cutting out the material at 6 in an angular or sort of V-like shape, providing beveled lower corners or tongues 5 at their ends. Said slots are within the margins 7 of the sheets which provide side 65 supporting webs for the loose depending tongues 5. Sheets 1, 2, are assembled by passing the tongues 5 of the front sheet through the slots 4 of the rear sheet, so that said tongues of the front sheet will lie behind or overlap the transverse webs 8 of the rear sheet. Such over-lapping tongues and webs provide spaces 9 therebetween in which cards 3 may be slid edgewise, (see Fig. 4), serving as guiding means for the 75 cards when inserted in the slots of the front sheet to prevent the lower edges of the cards from passing through a lower slot of the front sheet and to keep the lower portions of the cards between the members 80 of the two sheets. The cards 3 are shown provided with laterally extending projections 3^a at their edges along their tops adapted to rest along the upper edges 2^a at the ends of the slots, in front of the 85 tongues 5. Cards 3 may be slightly narrower throughout their length below the projections 3^a than the slots 4, so as to freely slide through the latter as illustrated in Fig. 1.

In order that opposite faces of the cards may be utilized for writing or printing thereon, and to retain the cards in the rack, the cards are shown provided at their lower ends with lateral projections 3^b, (Figs. 6 95 and 7), which will engage the edges of the material of sheet 1 at the slots 4 to prevent lifting the cards straight out of the slots. The lower portions of the cards are preferably scored at 3^c to provide hinges for the 100 upper portions of the cards, so that the cards may be pulled up to be stopped by the projections 3^b, and may be folded outwardly along the score lines 3^c, as indicated in Figs. 6 and 9, whereby the normally rearward surfaces of the cards may be utilized for writing or printing thereon. When the card is lifted, as described, it may be folded down in front of the rack, as in Figs. 6 and 7, to be observed or written upon, and 110 may be folded back against the rack and slid into its space 9. In order to insert the

lower portions of the cards having the lateral projections 3^b into the slots 4 of the front sheet, at least one edge of such card is recessed or slotted at 10, Figs. 6 and 7, whereby such edge of the card may be pushed along the adjacent vertical edge of slot 4^a to enter slot 10 with the card in an inclined position, such as shown in Fig. 7, the adjacent projection 3^b extending behind sheet 1, whereby the opposite projection 3^b may be slid through slot 4 and then the card may be shifted edgewise to locate it in proper position in slot 4. The card may be removed from the rack by reversing the operation last described. The projection 3^b serves the purpose of retaining the cards 3 in the rack for ordinary use against undesired displacement, but permitting the removal and replacement of the cards as required.

The rack device may comprise a plurality of pairs of sheets 1, 2, arranged back to back, so that opposite sides of the rack may have one or more vertical series of slots 4 and tongues 5, as illustrated in Figs. 1 and 2. The sheets 1, 2, may be of double width of the rack folded at 11, Fig. 2, and retained at their opposite edges by a binding strip 12, which may be glued to the sheets, or the sheets may be separate with binding strips 12 at opposite edges. A single pair of sheets 1, 2, is indicated in Fig. 3.

In order to indicate the hours at which appointments are made for association with cards 3, I provide sheet 1 with openings 13 adjacent to and at one side of the corresponding spaces that receive the cards, and in the space between sheets 1 and 2 I provide strips 14 adapted to slide or be adjusted behind the openings 13, which strips are provided with numerals 15 indicating units of time, such as hours of the day to appear through the openings 13. The rack may have a vertical row of openings 13 adjacent to each corresponding row of slots 4, and the rack may have one or more such rows of slots and openings, either on one or both sides of the racks.

When the rack is made with two pairs of sheets 1, 2, back to back, the cards 3 will enter the spaces between the series of sheets, and when the rack has a single pair of sheets at 1, 2, the lower parts of the cards will be free behind the rack. The openings 13 and strips 14 may be omitted if desired.

With the construction described a person may write the name of a party upon a card 3 and insert it in the rack to indicate an appointment with the party, or for keeping records on the card with relation to the party. When the openings 13 are used the strips 14 may be adjusted according to the needs of the user, such as according to his hours of business, and a card 3 having the name of an appointee thereon may be in-

serted in the appropriate slot adjacent to the hour of the appointment. If the appointment should be changed the corresponding card may be removed and replaced in another slot adjacent to the time opening for the new appointment. Data regarding the appointments or other business transactions may be written upon the cards containing the name of a party, as a record to indicate transactions with the party.

The cards may be slit at 16 into the projections 3^a, (Figs. 6 and 7), whereby the slots 16 may receive the sheet 1 at the ends of slots 4, by pushing the cards inwardly, to frictionally retain the cards on the sheet.

Having now described my invention, what I claim is:—

1. An appointment rack comprising adjacent sheets provided with spaced slots and having tongues, the tongues of one sheet extending through the slots of the adjacent sheet and depending below the slots thereof providing guideways for cards between the sheets, side portions of the sheets being attached together.

2. An appointment rack comprising adjacent sheets provided with spaced slots and having tongues, the tongues of one sheet extending through the slots of the adjacent sheet and depending below the slots thereof providing guideways for cards between the sheets, side portions of the sheets being attached together, said tongues at opposite ends having angular upwardly extending portions providing beveled lower corners at the ends of the tongues.

3. An appointment rack comprising adjacent sheets provided with spaced slots and having tongues, the tongues of one sheet extending through the slots of the adjacent sheet and depending below the slots thereof providing guideways for cards between the sheets, side portions of the sheets being attached together, one of said sheets having openings adjacent to the ends of said slots, and a strip between said sheets opposing said openings, said strip being provided with numerals representing units of time to show through said openings.

4. An appointment rack comprising adjacent sheets provided with spaced slots and having tongues, the tongues of one sheet extending through the slots of the adjacent sheet and depending below the slots thereof providing guideways for cards between the sheets, side portions of the sheets being attached together, and cards adapted to enter said slots, said cards having lateral projections at their upper and lower edges to retain the cards in the slots, said cards having means along their side edges to receive the edge of the front sheet adjacent to the slots to permit the projections at the lower ends of the cards to be passed through said slots.

5. An appointment rack comprising adjacent sheets provided with spaced slots and having tongues, the tongues of one sheet extending through the slots of the adjacent sheet and depending below the slots thereof of providing guideways for cards between the sheets, side portions of the sheets being attached together, and cards adapted to enter said slots, said cards having lateral projections at their upper and lower edges to retain the cards in the slots, said cards having slots in their side edges adapted to receive the material of the front sheet adjacent to the sides of its slots to permit the passage 15 of the lower projections of the cards through said slots.

6. An appointment rack comprising adjacent sheets provided with spaced slots and having tongues, the tongues of one sheet extending through the slots of the adjacent sheet and depending below the slots thereof of providing guideways for cards between the sheets, side portions of the sheets being attached together, and cards adapted to enter said slots, said cards having lateral projections at their upper ends and provided with slots entering said projections. 20 25

Signed at New York City, in the county of New York, and State of New York, this 9th day of December, A. D. 1921.

Z. AUERBACH.
